US00D466485S

(12) **United States Design Patent**
Maehara et al.

(10) Patent No.: **US D466,485 S**
(45) Date of Patent: ** Dec. 3, 2002

(54) **SEMICONDUCTOR PACKAGE**

(75) Inventors: **Kenichi Maehara, Kawagoe (JP); Koji Igarashi, Hanno (JP)**

(73) Assignee: **Shindengen Electric Manufactuturing Co., Ltd., Tokyo (JP)**

(**) Term: **14 Years**

(21) Appl. No.: **29/142,263**

(22) Filed: **May 23, 2001**

(51) LOC (7) Cl. **13-03**

(52) U.S. Cl. **D13/182**

(58) Field of Search **D13/182; D14/114; 174/52.1, 52.2, 52.4, 52.5, 16.3; 206/710, 719; 257/254, 659, 697, 730, 738; 324/755, 765; 361/752, 798, 850, 718, 730**

(57) **CLAIM**

The ornamental design for a semiconductor package, as shown and described.

DESCRIPTION

FIG. 1 is a front, plan and right side perspective view of a semiconductor package showing our new design;

FIG. 2 is a front, bottom and right side perspective view thereof;

FIG. 3 is a rear, plan and left side perspective view thereof;

FIG. 4 is a rear, bottom and left side perspective view thereof;

FIG. 5 is a front elevational view thereof;

FIG. 6 is a rear elevational view thereof;

FIG. 7 is a top plan view thereof;

FIG. 8 is a bottom plan view thereof;

FIG. 9 is a left side elevational view thereof; and,

FIG. 10 is a right side elevational view thereof.
